IGNITION APPARATUS

Walter J. Spengler, Sidney, N. Y., assignor to
 Bendix Aviation Corporation, New York, N. Y.,
 a corporation of Delaware

Application June 12, 1943, Serial No. 490,667

12 Claims. (Cl. 175—361)

1

This invention relates to electrical apparatus and more particularly to means for transforming voltages for firing the spark plugs in an ignition system of an internal combustion engine.

One of the objects of the present invention is to provide a novel and advantageous means for housing and mounting a plurality of spark coils of an ignition system.

Another object of the invention is to provide a simplified arrangement of a plurality of transformer coils in an ignition system wherein the current is distributed at primary or generated voltage and stepped up at coils mounted near the spark plugs.

A further object is to provide a structure embodying a novel arrangement of the above character which is sturdy and reliable and whereby a substantial saving of space and weight is realized without sacrificing any advantages of structures heretofore provided for the same purpose.

Another object is to provide apparatus of the above character whereby the radio-shielding required for the entire ignition system is reduced to a minimum, thereby materially reducing the possibility of failures.

Still another object is to provide apparatus of the above character which is so constructed that the operation thereof will not be affected by rarefied atmosphere and low pressures at high altitudes.

The above and further objects and novel features of the invention will more fully appear from the following detailed description when the same is read in connection with the accompanying drawing. It is to be expressly understood, however, that the drawing is for the purpose of illustration only and is not intended to define the limits of the invention, reference for this latter purpose being primarily had to the appended claims.

In the drawing, wherein like reference characters refer to like parts throughout the several views,

Fig. 1 is a side elevation view mostly in section and with parts broken away showing one form of structure embodying the features of the present invention, the section being taken substantially on line 1—1 of Fig. 2;

Fig. 2 is a top plan view of the structure shown in Fig. 1 with the cover and filling material removed;

Fig. 3 is a detail plan view, partly in section, showing the main casing of the structure of Fig. 2; and,

Fig. 4 is a detail sectional view with parts

2

broken away, the section being taken substantially on line 4—4 of Fig. 2.

A single embodiment of the present invention is illustrated in the accompanying drawing, by way of example, in the form of a nest of four transformer coils 10, which is particularly adapted for use on a double row radial engine having dual ignition. As illustrated, each of the four coils are identical, and hence interchangeable, thereby minimizing manufacturing and installation costs and problems and facilitating replacements when necessary. Each of said coils consists of the usual primary and secondary windings wound on a metallic core 11, said windings being enclosed in a cylindrical casing 12 of insulating material. Each of the cores 11 consists of a plurality of rectangular laminations, each having an arm 13 extending through the coil, a similar arm 14 extending parallel to arm 13 at the periphery of the coil and two radially extending arms 15 and 16 at the ends of the coils connecting the ends of arms 13 and 14.

Coils 10 with their input and output terminals, to be hereafter described, are preferably enclosed and, hence, radio-shielded by a two-part metallic housing consisting of a substantially cylindrical main casing member 17 and a cover 18. The closed end or bottom 19 of casing member 17 is provided on its inner face with a groove or recess 20 in the form of a cross (Fig. 3) for receiving the positioning arms 15 of the coil cores, said cores being arranged with the exposed arms 14 thereof adjacent one another at the center of casing 17.

At any convenient position at the closed end 19 of casing member 17, an opening 21 is provided for incoming conductors from a source of current which feeds the primary windings of coils 10. A multiple socket 22 of a plug and

socket connection, which may be of any suitable type, such as those known as "Cannon" plugs, is mounted in opening 21 and each of the socket conductors 23 is connected by an insulated lead 24 to the primary winding of a coil 10. As seen in Fig. 1, the thickness of core arms 15 is greater than the depth of recess 20 by a sufficient amount to permit conductors 24 to pass between bottom closure 19 and the lower ends of coils 10. The plug of the detachable connector may be removably held in place by a nut which engages the threaded portion 25 of socket 22 in a manner well understood in the art.

Cover 18 is preferably provided with a depending annular flange 26 which closely surrounds the upper edge of casing 17. Any suitable means,

such as screws 27, may be provided for securing the cover to casing member 17. Screws 27 may engage threaded openings 28 tapped into bosses 29 on the interior of said casing member (Fig. 2). The inner face of cover 18 is provided with a groove 30 similar to and directly opposite groove 20 for receiving and positioning arms 16 of coil cores 11. The core and coil assemblies 10, 11 are thus firmly held in predetermined positions in casing 17, 18. If desired, a spacer 31 of wood or other suitable material may be inserted between arms 14 of coil cores 11 at the center of casing member 17. Cover 18 is also provided with four symmetrically-spaced, externally-threaded nipples 32 for a purpose to appear hereinafter, said nipples being disposed directly above and concentric with four circular recesses 33 in bottom 19 of casing member 17.

Before cover 18 is placed in position, suitable sockets with terminals connected to the output ends of the secondary windings 34 of coils 10 and adapted to receive detachable plug connectors are installed in casing member 17 and the connected ends of the primary and secondary windings of each coil are connected to ground by means of insulated leads 35 which are conductively attached to casing 17 by any suitable means, such as screws 36. Each of the sockets for a high tension or output terminal comprises a rigid insulating tube 37, the upper end of which has a close sliding fit in a nipple 32 of cover 18. The lower end of each tube 37 rests upon a block 38 of suitable insulating material, which is, in turn, positioned in the bottom of casing member 17 by a recess 33 or held in place by means of glue or the like for assembly purposes.

Resting on an internal shoulder 39 intermediate the ends of tube 37 is a fabricated terminal 40 which comprises a washer or plate 41 engaging said shoulder and a depending coil spring 42. The lower hooked end 43 of said spring operatively engages a rigid metallic bracket 44, which is secured to the wall of coil casing 12 (Fig. 4) and is electrically connected to the high voltage end of secondary winding 34 of the coil. The laterally extending portion of bracket 44 to which spring 42 is hooked extends through a groove or slot 45 in the lower end of socket tube 37 and, hence, serves to limit the angular movement of the tube about its longitudinal axis. Since spring 42 is extensible and retractable, the same materially facilitates the assembly of the coils and sockets and insures against the possibility of flashovers in the assembled unit by keeping the high tension conductors within tube 37 insofar as is possible and, hence, a maximum distance from any grounded metal parts.

A spring 46 may be connected to terminal 40 for making contact with a connector plug (not shown) adapted to be received by socket tube 37 and to be detachably secured to nipple 32 by means of a nut 47 in a manner well understood in the art. A shielded lead 48 from the connector plug may extend to a spark plug in an engine or other point of use for the high tension current from secondary winding 34.

For the purpose of providing further assurance against flashovers from the high tension conductors and terminals to the other metallic parts of the structure and of obviating the bad effects of changes in pressures resulting from changes in altitude, the entire space around coils 10 and sockets 37 within casing 17, 18 is preferably filled with an insulating compound. Polymers of cashew-nut-shell oil or linseed oil have

been found satisfactory for this purpose. The filling material is preferably injected with the aid of vacuum or pressure while in the form of a viscous liquid. A suitably drying or setting agent, such as paraformaldehyde or the like, may be mixed with the liquid polymers to facilitate setting thereof throughout without the aid of oxygen. Heat may be applied to facilitate the setting action. It is preferable that the filling material used be of such a nature that it will set to a yieldable but non-moldable solid form which will permit removal of the coils and filling material from the casing without damage to the coils when disassembly of the unit is necessitated.

During the filling operation, socket tubes 37 above terminals 40 may be substantially filled with a suitable plug to prevent the compound from filling the well which is intended for the connector plug. Many types of suitable connector plugs are well-known in the art and in common use today. The filling material may be injected through a filling hole 49 while air or other gases are permitted to escape through a bleed port 50.

To further provide against the possibility of flashovers within casing 17, 18, a piece of varnished cambric 51 or like insulating material may be passed between each coil and arm 14 of the core thereof and extend between the terminal socket 37 attached to said coil and the casing of an adjacent coil (Fig. 2). This provides insurance against flashovers from the high tension terminals and particularly brackets 44 to the cores 11 of the coils.

Casing member 17 is preferably provided with an external flange 52 which, together with the extending portion 26 of cover 18, forms an external channel to receive suitable means for mounting the coil unit on an engine. The mounting means preferably comprise some suitable yieldable material so that all the vibrations and shocks of the engine will not be transmitted to the coil unit. The novel coil unit disclosed is particularly adapted to be mounted between two adjacent cylinders in the front row of a double row radial engine so that it may serve four spark plugs located near it, such as the spark plugs in one rear row cylinder and one front row cylinder of a double row, radial engine. Only a relatively short shielded lead 48 between each of the terminals 40 and a spark plug of the engine is thus required. The four input leads entering socket 22 from a suitable distributor may be shielded in a single conduit which may, in turn, extend from a shielding harness manifold of any suitable type well-known in the art.

There is thus provided a novel structure whereby a plurality of ignition coils adapted for use in a low tension ignition distribution system may be simply and compactly arranged in a substantially air-tight casing and yet provide ample protection against flashovers and ample radio-shielding. Additionally, the coil unit provided is sturdy and reliable in use and may be conveniently and advantageously mounted on the engine. The readily detachable electrical connections make it possible to renew the leads which deteriorate in use more readily than most other parts of an ignition system. The detachable leads also facilitate assembly and installation.

Although only a single embodiment of the invention is illustrated and described, it is to be expressly understood that the same is not limited thereto. For example, the number and arrangement of the coils may be varied, such as by plac-

ing the same in a single line in an oblong casing. Various other changes, particularly in the arrangement and design of the parts illustrated, may be made without departing from the spirit and scope of the invention, as will now be apparent to those skilled in the art. For a definition of the limits of the invention, reference is had primarily to the appended claims.

What is claimed is:

1. In apparatus of the class described, a metallic casing comprising a body portion and a cover removably secured thereto, said cover having a plurality of outlets therein, a plurality of ignition coils in said casing, each having primary and secondary windings, a metallic core for each of said coils forming a magnetic flux path around a portion of the latter, opposed recesses in said body portion and cover for receiving portions of said cores to position said coils in said casing, an insulating tube adjacent each coil, each of said tubes slidably extending into one of said outlets in the cover, a terminal in each of said tubes, means connecting each of said terminals to the high potential end of the secondary winding of an adjacent coil, a socket of a multiple plug and socket connector in said body portion, means connecting the terminals of said socket to the ungrounded ends of the primary windings of said coils, and means connecting the adjacent ends of the primary and secondary windings of each coil to the casing interiorly thereof for grounding the same.

2. In apparatus of the class described, a metallic casing comprising a body portion and a cover removably secured thereto, said cover having a plurality of tubular outlets therein, a plurality of ignition coils in said casing, each having primary and secondary windings, a metallic core for each of said coils forming a magnetic flux path around a portion of the latter, said body portion and cover having opposed internal recesses for receiving portions of said cores to position said coils in said casing, an insulating tube adjacent each coil, each of said tubes slidably extending into one of said outlets, a terminal in each of said tubes, means including an extensible resilient conductor under tension connecting each of said terminals to the high potential end of the secondary winding of an adjacent coil, a socket of a multiple plug and socket connector in said body portion, means connecting the terminals of said socket to the ungrounded ends of the primary windings of said coils, means connecting the adjacent ends of the primary and secondary windings of each coil to the casing interiorly thereof for grounding the same, and a filler of yieldable solid insulating material in a dry non-moldable state filling the space in said casing around said coils and tubes and filling said tubes around said terminal connecting means.

3. In apparatus of the class described, a metallic casing comprising a substantially cup-like body and a cover removably secured to the open end of said body, oppositely facing internal recesses in the bottom of said body and said cover, said casing being filled with insulating material and containing a plurality of transformer coils having primary and secondary windings, a metallic core for each of said coils, each of said cores comprising a pair of spaced arms extending longitudinally of the coil, one of said arms extending through the central opening in said coil, and a pair of arms extending between the adjacent ends of said first-named arms, said

second-named pair of arms extending into said recesses to position said coils in said casing, an elongated socket extending longitudinally of each coil and communicating with the exterior of said casing, and a terminal in each of said sockets connected with the secondary winding of an adjacent coil.

4. In apparatus of the class described, a metallic casing comprising a substantially cup-like body and a cover removably secured to the open end of said body, oppositely facing internal recesses in the bottom of said body and said cover, a plurality of transformer coils having primary and secondary windings, and a metallic core for each of said coils, each of said cores comprising a pair of spaced arms extending longitudinally of the coil, one of said arms extending through the central opening in said coil and a pair of arms extending between the adjacent ends of said first-named arms, said second-named pair of arms extending into said recesses to position said coils in said casing, said coils being arranged in the casing with the external longitudinally extending arms of said cores adjacent the center of the casing and with the coils and their connections set in solidified insulation.

5. In apparatus of the class described, a metallic casing comprising a substantially cup-like body and a cover removably secured to the open end of said body, said cover having a plurality of outlets therein, oppositely facing internal recesses in the bottom of said body and said cover, a plurality of transformer coils having primary and secondary windings, a metallic core for each of said coils, each of said cores comprising a pair of spaced arms extending longitudinally of the coil, one of said arms extending through the center opening in said coil and a pair of arms extending between the adjacent ends of said first-named arms, said second-named pair of arms extending into said recesses to position said coils in said casing, an elongated insulating tube adjacent each coil having the upper end thereof slidably extending into one of said outlets, a terminal in each of said tubes, and means including an extensible resilient conductor for detachably connecting each of said terminals to the secondary winding of an adjacent coil.

6. In apparatus of the class described, a metallic casing comprising a body portion and a cover removably secured thereto, a plurality of ignition coils in said casing, each of said coils having a primary winding, and a secondary winding and terminals connected therewith, and a closed metallic core for each of said coils forming a magnetic flux path around a portion of the latter, said body portion and cover having opposed internal recesses into which radially extending portions of said cores at opposite ends of said coils fit for positioning said coils in said casing, and said casing being filled with insulating material whereby the coil and its connections are protected against shock and insulated against flashovers.

7. In apparatus of the class described, an insulation-filled, metallic casing comprising a body portion and a cover removably secured thereto, said cover having a plurality of outlets therein with insulation-retaining means separating their outer from their inner portions, a plurality of ignition coils in said casing, each of said coils having a primary winding and a secondary winding, a closed metallic core forming a magnetic flux path around a portion of each of said coils, said body portion and cover having opposed re-

cesses into which radially extending portions of said cores at opposite ends of said coils fit for positioning said coils in said casing, said coils being arranged with the longitudinally extending portions of the cores outside said coils adjacent the center of the casing, and an elongated insulating socket communicating with each of said outlets and extending longitudinally of said coils, and a terminal in each of said sockets connected with the secondary winding of an adjacent coil.

8. In apparatus of the class described, a two-part metallic casing, at least one of said parts having a plurality of outlets therein, means for removably securing said parts together to form a closed casing, a plurality of ignition coils in said casing, each of said coils having a primary winding and a secondary winding, a substantially closed metallic core for each of said coils forming a magnetic flux path around a portion of the latter, said casing parts having opposed internal recesses therein into which radially extending portions of said cores at opposite ends of the coils fit for positioning said coils in the casing, a tube of insulating material adjacent each coil, a portion of each of tubes slidably extending into one of said outlets, a terminal in each of said tubes intermediate the ends thereof whereby said tubes serve as sockets for removable plug connectors, and means for connecting each of said terminals to the high potential end of the secondary winding of an adjacent coil.

9. In apparatus of the class described, a two-part metallic casing, at least one of said parts having a plurality of outlets therein, means for removably securing said parts together to form a closed casing, a plurality of ignition coils in said casing, each of said coils having a primary winding and a secondary winding, a substantially closed metallic core for each of said coils forming a magnetic flux path around a portion of the latter, said casing parts having opposed internal recesses therein into which radially extending portions of said cores at opposite ends of the coils fit for positioning said coils in the casing, a tube of insulating material adjacent each coil, a portion of each of said tubes slidably extending into one of said outlets, a terminal in each of said tubes intermediate the ends thereof whereby said tubes serve as sockets for removable plug connectors, means for connecting each of said terminals to the high potential end of the secondary winding of an adjacent coil, a unitary plug and socket connector for connecting the primary windings of said coils to a source of electrical energy, and means connecting the adjacent ends of the primary and secondary windings of each coil to the casing for grounding the same.

10. In apparatus of the class described, a two-part metallic casing, at least one of said parts having a plurality of outlets therein, means for removably securing said parts together to form a closed casing, a plurality of ignition coils in said casing, each of said coils having a primary winding and a secondary winding, a substantially closed metallic core for each of said coils forming a magnetic flux path around a portion of the latter, said casing parts having opposed internal recesses therein into which radially extending

portions of said cores at opposite ends of the coils fit for positioning said coils in the casing, a tube of insulating material adjacent each coil, a portion of each of said tubes slidably extending into one of said outlets, a terminal in each of said tubes intermediate the ends thereof whereby said tubes serve as sockets for removable plug connectors, means for connecting each of said terminals to the high potential end of the secondary winding of an adjacent coil, and a yieldable solid insulating material in a dry, non-moldable state filling the space in said casing around said coils and tubes and filling said tubes around said terminal connecting means.

15 11. In apparatus of the class described, a metallic casing comprising a substantially cup-like body and a cover removably secured to the open end of said body, said cover having a plurality of outlets therein, oppositely facing cross-shaped recesses in the bottom of said body and said cover, a plurality of transformer coils having primary and secondary windings, a metallic core for each of said coils, each of said cores comprising a pair of spaced arms extending longitudinally of the coil, one of said arms extending through the central opening in said coil, and a pair of arms extending between the adjacent ends of said first-named arms, said second-named pair of arms extending into said recesses to position said coils in said casing, an elongated insulating tube adjacent each coil having the upper end thereof slidably extending into one of said outlets, a terminal in each of said tubes, means including an extensible conductor for removably connecting each terminal to the secondary winding of an adjacent coil, and yieldable solid insulation in a dry non-moldable state surrounding said coils and tubes in said casing.

12. In apparatus of the class described, a metallic casing comprising a substantially cup-like body and a cover removably secured to the open end of said body, said cover having a plurality of outlets therein, oppositely facing cross-shaped recesses in the bottom of said body and said cover, a plurality of transformer coils having primary and secondary windings, a metallic core for each of said coils, each of said cores comprising a pair of spaced arms extending longitudinally of the coil, one of said arms extending through the central opening in said coil, a pair of arms extending between the adjacent ends of said first-named arms, said second-named pair of arms extending into said recesses to position said coils in said casing, an elongated insulating tube adjacent each coil having the upper end thereof slidably extending into one of said outlets, a terminal in each of said tubes, means including an extensible conductor for detachably connecting each terminal to the secondary winding of an adjacent coil, yieldable solid insulation in a dry non-moldable state surrounding said coils and tubes in said casing, and a thin sheet of insulating material, such as varnished cambric, extending between each coil and the longitudinally extending external core arm of the core therefor and between the terminal tube for said coil and an adjacent coil.

WALTER J. SPENGLER.
